UNITED STATES PATENT OFFICE.

BERT R. BENJAMIN, OF OAK PARK, ILLINOIS, ASSIGNOR TO INTERNATIONAL HARVESTER COMPANY, A CORPORATION OF NEW JERSEY.

GRAIN-BINDER.

1,029,659.

Specification of Letters Patent. Patented June 18, 1912.

Application filed January 15, 1912. Serial No. 671,323.

To all whom it may concern:

Be it known that I, BERT R. BENJAMIN, a citizen of the United States, residing at Oak Park, in the county of Cook and State 5 of Illinois, have invented certain new and useful Improvements in Grain-Binders, of which the following is a specification.

My invention relates to grain binders, and in particular to improved means for retarding the descent of the heads of the grain 10 as it moves downward upon the inclined deck of the binder attachment of a harvester during the operation of the packers in forming a bundle.

It consists of a retarding member having 15 one end thereof pivotally connected with one of the discharge arms of the grain binder in a manner whereby a limited swinging movement thereof is permitted and having the opposite end thereof adapted to contact with the deck of the grain binder during the time a bundle is being formed, the object of my invention being to provide a construction that will perform its function 20 of a retarder while the grain is being packed by the packers and will be removed from the deck while the discharge arms are ejecting the sheaf and thereby relieve the discharge arms of so much of the power required to force the grain beyond the end of 25 the retarder as is necessary when the common form of spring-pressed retarder is used. These objects are attained by means of the mechanism illustrated by the accompanying 30 drawing, in which—

Figure 1 is an end elevation of part of a grain binder having my invention embodied in its construction and Fig. 2 is a side view 35 of part of Fig. 1 designed to illustrate the manner of connecting the grain retarder with one of the discharge arms of the binder attachment.

The same reference characters designate like parts throughout the several views.

1 represents the inclined deck of a grain binding attachment; 2 the packer fingers; 3 the trip and compressor arm; 4 the knotter actuating shaft having the discharge arms 45 secured thereto; 6 a knotter actuating

wheel secured to shaft 4; 7 the knotter frame 50 having the knotter shaft journaled therein; 8 the breast plate secured to the knotter frame; 9 the discharge arm stripper, all of the above named parts being common in the class of machines indicated. 55

10 represents a grain retainer comprising a flat bar having a slotted opening at one end thereof that receives one of the discharge arms, and provided with transversely arranged eye portions upon opposite 60 sides of the open end of the slot that receive a pivot bolt 11 whereby the retainer is pivotally connected with the discharge arm in a manner permitting a limited swinging movement of the retainer relative 65 to the discharge arm. The retainer has a length that, when the discharge arm is at the end of its sheaf discharging movement, the opposite end of the retainer will rest upon the deck of the grain binder and the 70 retainer will incline outward and upward in a manner preventing any outward swing of the lower end thereof as the bundle is being formed, and the discharge arm carries it upward and over the knotter actuating shaft as shown by dotted lines in Fig. 1, when the sheaf is being ejected, and when the discharge arm is nearing the end of its revolution the retainer swings downward to a sheaf receiving position. 75

What I claim as my invention, and desire to secure by Letters Patent, is:

1. A grain binder having, in combination, a deck, a knotter, a rotatable knotter actuating shaft, a discharge arm secured to said 85 shaft, and a grain retainer carried by said discharge arm.

2. A grain binder having, in combination, a deck, a knotter, a rotatable knotter actuating shaft, a discharge arm secured to said 90 shaft, and a grain retainer having one end secured to said discharge arm and the opposite end thereof engaging with said deck when said discharge arm has reached the limit of its sheaf discharging movement. 95

3. A grain binder having, in combination, a deck, a knotter, a rotatable knotter actuating shaft, a discharge arm secured to said

shaft, a grain retainer having an open-ended slot at one end thereof and eye portions upon opposite sides of said slot, a bolt received by said eye portion whereby said 5 retainer is pivotally connected with said discharge arm in a manner having a limited swinging movement thereon, the opposite

end of said retainer engaging with said deck when said discharge arm has reached the limit of its sheaf discharging movement.

BERT R. BENJAMIN.
